UNITED STATES PATENT OFFICE.

WILLIAM POPE, OF ROCKVALE, TENNESSEE.

GATE.

1,335,350.

Specification of Letters Patent. Patented Mar. 30, 1920.

Application filed March 1, 1919. Serial No. 280,069.

To all whom it may concern:

Be it known that I, WILLIAM POPE, a citizen of the United States, residing at Rockvale, in the county of Rutherford and 5 State of Tennessee, have invented certain new and useful Improvements in Gates, of which the following is a specification.

The object of this invention is to provide a gate which will be normally held in closed 10 position and which may be opened by a pedestrian, or by the occupants of a vehicle without dismounting from the vehicle. The invention seeks to provide a gate of the stated character which will be automatically 15 closed after a pedestrian or vehicle has passed through the gateway and also to provide a construction in which the operating mechanism will be protected from the weather so that it will be always in operative 20 condition. A further object of the invention is to provide means whereby the gate will be held to a rectilinear path and also to provide means whereby snow, ice and sleet will be prevented from accumulating 25 upon the top rail of the gate so as to render the operation thereof difficult. These stated objects and other objects which will incidentally appear in the course of the following description are attained in mechanism 30 such as is illustrated in the accompanying drawings and the invention resides in certain novel features which will be particularly pointed out in the claims following the description.

35 In the accompanying drawings:

Figure 1 is an elevation of a gate embodying my present improvements, the gate being shown in its closed position and parts being broken away;

40 Fig. 2 is a sectional elevation showing the gate in the opened position;

Fig. 3 is a horizontal section on the line 3—3 of Fig. 1;

45 Fig. 4 is a perspective view of the upper corner of the gate showing the gate in its opened position;

Fig. 5 is a detail transverse section on the line 5—5 of Fig. 2;

50 Fig. 6 is a detail sectional elevation showing the gate opened and also showing the means provided for holding the gate in its opened position;

Fig. 7 is a perspective view showing the connections between the gate and the runways provided to receive the wheels of a 55 passing vehicle;

Fig. 8 is a detail perspective view of the outer end of a runway;

Fig. 9 is a perspective view of the fence post which receives and holds against lateral movement the free end of the gate.

The gate comprises posts 1 and rails 2 secured to and extending horizontally between the posts, the posts being equipped at their lower ends with rollers 3 to travel on a rail 4 which is provided on the upper side of a sill 5 which is embedded in the roadway in the line of the fence. A brace 6 is also provided and secured to the end posts 1 and the rails 2 of the gate so as to attain the desired 65 rigidity in the structure. At one side of the roadway, I provide a fence post 7 to which the fence rails 8 are secured in the usual manner and in that side of the fence post facing the road, I form a vertical recess 9 which is adapted to receive the free end 70 of the gate and thereby support the same against lateral movement when it is closed and also resist strains or blows exerted upon the gate by stock or from other causes. The 75 track rail 4 terminates within the lower end of the recess 9 so that the gate may freely enter the recess and positively engage the same. At the opposite side of the roadway, I provide a casing or housing 10 which ex- 80 tends substantially in the line of the fence and the bottom or floor of which may be a continuation of the sill 5 if preferred. The track rail 4 enters the housing and extends to the closed end of the same so that the gate 85 will be held to a rectilinear path in all its movements and may enter the casing so as to be completely housed thereby and leave the entire roadway clear for the passage of a 90 vehicle. The top of the housing is constructed to provide upper and lower longitudinal grooves or guides and to close the housing so that while the gate will be held to a rectilinear path, snow and rain or other 95 elements cannot obtain access to the housing so as to prevent the operation of the actuating mechanism. In Fig. 5, the top of the housing is shown as consisting of a beam 11 extending longitudinally of the housing and provided in its under side with a longi- 100 tudinal central groove 12 to receive the top rail 2 of the gate, and side bars 13 secured to the side walls of the housing and having their inner edges spaced apart and resting upon the beam 11 whereby a groove 14 is 105 provided to receive a rib 15 on the under side of a cap plate 16 which is connected to

the top of the gate. This construction is also shown in Fig. 4 and is a convenient method of constructing the top of the housing, but it is to be understood that the members 11 and 13 may be integral or may be otherwise formed. As shown most clearly in Fig. 7, the cap plate 16 is widened, as shown at 17, at the inner end of the gate so that the widened portion of the cap plate 10 will extend over the full width of the housing and is provided with depending flanges 18 along the side edges of said widened portion which engage the side walls of the housing and so thoroughly protect the housing 15 against the elements. The cap plate is obviously spaced above the top rail of the gate and to support the forward or free end thereof, a bracket 19 is secured to the outer end post 1 of the gate and the end of the rib 15, 20 as shown clearly in Fig. 4. In the normal closed position of the gate, the widened portion 17 of the cap will cover the housing while the narrower portion thereof will extend over the gate to the fence post and its 25 free end will cover the upper end of the recess 9 in said post. The entrance of snow, rain or sleet to all the parts will thus be prevented, so that in all weather the gate will be in an operative condition.

30 To hold the gate normally closed and to automatically return it to closed position after it has been opened, I provide mechanism within the housing which will exert a constant closing force upon the gate but 35 which will yield readily to an opening movement when the gate is pushed within the housing. This mechanism consists of a lazy tongs 20, the foremost or outermost link 21 of which is pivoted at its free end to the 40 inner or rear post 1 of the gate and the innermost or rearmost link 22 of which is pivoted to the inner or rear wall of the housing, as shown at 23, and it may be here noted that throughout this description the terms 45 "inner" and "outer" or "forward" and "rearward" are relative only and are employed for convenience in referring to the parts, the free end of the gate or that end which engages the fence post in the closed position 50 being considered the outer or forward end and the terms being used with the same meaning when applied to other parts. Within the housing, adjacent the forward or outer end thereof, I provide the posts or 55 standards 24 to or in which are fulcrumed the levers 25, the inner or rear ends of the levers being equipped with weights 26 which should be sufficiently heavy to hold the inner ends of the levers normally down, 60 as shown in Fig. 1. As shown in Fig. 3, a post 24 is provided at each side of the housing and a lever 25 is fulcrumed in each post. The forward or free ends of the levers project through the forward end of the housing 65 and play in vertical slots 27 therein, suspen-

sion hooks 28 being hung in the free ends of the levers, as shown clearly in Figs. 2 and 7. These suspension hooks are adapted to be engaged by links 29 at the ends of treadles 30 mounted in runways 31 disposed upon the ground at the opposite sides of the gate and extending longitudinally of the road as will be readily understood. These treadles are supported at their outer ends upon the floor of the runway by a pivotal connection 32 and their inner ends are supported normally in an elevated position by the hooks 28 and links 29. Guide ribs 33 are provided on the upper sides of the treadles so that the wheels of a vehicle driven into the runway will be held to a path extending longitudinally of the runway but at a sufficient distance from one edge of the runway to prevent the hubs of the vehicle wheels striking against any projecting part of the end of the gate or the 80 housing and thereby damaging either the vehicle or the gate. Hangers 34 are pivoted at their upper ends to the pivotal connection between the end of the link 22 and the adjacent link of the lazy tongs and the lower 85 ends of said hangers are pivoted, as shown at 35, to the immediately adjacent lever 25. It will be readily understood that when a vehicle is driven into a runway, the treadle 90 30 therein will be depressed by the weight of the vehicle and the load carried by it so that the inner weighted end of the lever connected with said treadle will be swung upwardly and, consequently, the lazy tongs will be retracted or folded, as shown in 95 Fig. 2, and the gate opened or drawn inwardly. The runway should be of such length that as or before the front wheel of the vehicle leaves the same the back wheel 100 will enter it so that the treadle will be held depressed until the vehicle has passed through the gate and to further serve this object the adjacent ends of the runways will be spaced apart only enough to permit the gate to pass between them so that when the 105 vehicle wheel leaves one runway it will immediately enter the other and, consequently, the operating levers 25 will be held in the position shown in Fig. 2 until the vehicle has 110 entirely passed through the gateway and the rear wheels thereof have cleared both runways. As soon as the vehicle is entirely clear of the runways the weights 26 will descend and will thereby exert an opening or 115 extending force upon the lazy tongs so that it will resume the position shown in Fig. 1 and project the gate across the roadway to its closed position.

A pedestrian desiring to pass through the gateway will merely press upon the treadle 120 with one foot and then step through the gateway, the lazy tongs acting automatically to return the gate to closed position so that the hands of the pedestrian are free to carry bundles. Should a horseback rider desire to 125 130

pass through the gateway he will exert sufficient manual pushing force upon the gate to open the same and to facilitate the opening of the gate by the horseman a knob 36 5 is provided on the cap plate 16 near the outer or forward end thereof, as shown in Figs. 1 and 2.

Should it be desired for any reason to hold the gate open for a considerable period 10 it is pushed back to the limit of its movement, as shown in Fig. 2, and a hook 37, secured upon the housing at one side of the passage therein for the gate, is engaged in a hasp or eye provided on the end wall of the 15 housing at the opposite side of the passage for the gate so as to extend across the end of the gate, as shown in Fig. 6. This provision will be found advantageous when it is desired to drive stock through the gateway or 20 a number of vehicles arrive at the gate at the same time. When the hook is disengaged from the eye the gate will automatically shut under the influence of the lazy tongs, as previously described.

25 From the foregoing description, taken in connection with the accompanying drawings, it will be seen that I have provided a gate which is particularly adapted for use upon farms and in which the operating mechanism will be thoroughly protected from the weather. The gate will be held normally closed but may be easily opened and after the opening force is released the gate will automatically close. The construction and 30 arrangement of the parts is simple so that the cost of installing the gate will be low and the cost of maintenance will be negligible. The gate may be installed on a lawn or across a footpath in which event, the runways may be omitted and the treadles may 35 rest on the ground or on a block sunk therein.

Having thus described the invention, what is claimed as new is:

40 1. The combination of a gate mounted to move in a rectilinear path, posts disposed at the opposite sides of the said path and adjacent the sides of the passage closed by the gate, a lazy tongs connected at one end to the end of the gate and at its opposite end to a fixed support and disposed between the 45 said posts, levers fulcrumed intermediate

their ends upon the said posts and disposed longitudinally of and immediately adjacent the lazy tongs, treadles disposed at opposite sides of the gate with their higher ends immediately adjacent the gate, links connecting the higher ends of the treadles with the ends of the levers respectively above the treadles, hangers connecting the opposite 55 ends of the levers with that member of the lazy tongs which is pivoted to the fixed support, and means on the last-mentioned ends of the levers for overbalancing the treadles.

2. In a gate, the combination of a housing, 60 a gate mounted for movement into and out of said housing, means within the housing to hold the gate normally projected therefrom, a cap plate extending over the housing and connected at its free end to the free 65 end of the gate, and means on the housing and the cap plate for guiding the same.

3. The combination of a housing having a longitudinal groove in its top, a gate having its top rail arranged to engage slidably in 70 said groove, and means within the housing 75 acting on the gate to hold the gate normally closed.

4. The combination of a housing having longitudinal grooves in the upper and lower 80 sides of its top, a gate having its top rail arranged to slidably engage the lower of said grooves, means within the housing for holding the gate normally closed, a cap plate extending over the housing and having its 85 free end connected with the free end of the gate whereby the cap plate will move with the gate, and a rib on the under side of said cap plate engaging the upper groove in the top of the housing.

5. The combination of a housing, a gate 90 movable into and out of the housing, means within the housing acting on the gate to hold it normally out of the same, a longitudinal groove in the upper side of the housing, a cap plate fitting over the housing and having its free end connected with the free end of the gate, a rib on the under side of the cap plate engaging the groove in the housing and depending flanges at the side 95 edges of the cap plate engaging the sides of the housing.

In testimony whereof I affix my signature.

WILLIAM POPE. [L. S.]
